UNITED STATES PATENT OFFICE.

SAMSON D. WRIGHT, OF CLEVELAND HEIGHTS, OHIO.

DRIVING MECHANISM.

1,386,667.

Specification of Letters Patent. Patented Aug. 9, 1921.

Application filed June 9, 1919. Serial No. 302,773.

To all whom it may concern:

Be it known that I, SAMSON D. WRIGHT, a citizen of the United States, residing at Cleveland Heights, in the county of Cuyahoga and State of Ohio, have invented certain new and useful Improvements in Driving Mechanism, of which the following is a specification.

This invention relates to driving mechanism such as is used for railway cars, for example, coke cars, charging cars, or any other railway cars operated by their own power.

The object of the invention is to provide improved driving mechanism of unit form adapted for simple attachment to the car, and which safely suspends and protects the electric motor and provides convenient access to the driving gears and shaft for purposes of replacement, repair or inspection. A further object of the invention is to provide driving mechanism including a simple form of speed reducing gearing wherein the number of intermediate shafts is reduced and the power transmitted from the motor to the car axle through a minimum number of gears, thereby reducing friction and loss of power in the gearing.

Further objects of the invention are in part obvious and in part will appear more in detail hereinafter.

In the drawings, which represent one suitable embodiment of the invention, Figure 1 is a plan view illustrating a portion of the car frame with the driving mechanism applied thereto; Fig. 2 is a sectional elevation on the line 2-2, Fig. 1, portions being broken away to expose interior parts; and Fig. 3 is a horizontal section on the line 3-3, Fig. 2, the motor being shown in plan view.

Referring to the drawings, 1 indicates a portion of the car frame, which may be of any suitable form or construction and requires no further description. 2 indicates one of the car axles rotatable in bearings in the frame, as is usual, and provided with a wheel 3.

The unit driving mechanism includes a suitable inclosing casing for the gearing which may also be formed to support and protect the driving motor. In the form shown in the drawings said casing includes a body portion 4 having a semi-circular seat 5 to support an electric motor 6, an axle housing portion 7 secured to the body por-

tion 4 at the meeting faces 8 by bolts 9, so that said body portion and axle housing portion surround the axle 2 as shown in Fig. 2, and a cover or cap 10 for the motor which is hinged to the body portion 4 at 11 and is secured at its other end to said body portion by bolts 12.

This arrangement enables the casing to be securely bolted in position around the axle and to firmly clamp, support and protect the electric motor, as will be obvious. Preferably the body portion 4 and axle housing portion 7 of the casing carry bearing members 13 surrounding the axle 2 and held in place by split collars 14, as shown in Fig. 3. Consequently, the axle 2 can rotate in the housing and said housing also has slight oscillating or self-adjusting motion about the axle with vibration of the car. To reduce the shock and jar the other end of the casing opposite to the axle is yielding supported, such as by being provided with an eye 15 resting on a compression spring 16 supported by a portion of the fixed frame 1. Above said eye is a second compression spring 17 lying beneath a collar 18 held on the end of a bolt 19 passing through said two springs, the eye 15 and the fixed frame 1. By screwing up the nuts 20 the pressure of the two springs 16, 17 may be adjusted, and the entire mounting enables the eye 15 to vibrate back and forth on the bolt 19 against the pressure of the springs and absorb shock, jar and vibration which otherwise would be transmitted to the motor and driving mechanism.

The motor shaft 21 at one end is provided with a driving pinion 22 held thereon by a nut 23 and washer 24, by removing which said pinion can be readily taken off. Said pinion is in meshing relation with a large gear 25 keyed to one end of a shaft 26 which rotates in bearings 27 and 28 held in openings in the casing body 4. Intermediate its end said shaft has keyed thereon a pinion 29 in driving relation with a large gear 30 lying within a hollow chamber 31 between the casing portions 4 and 7 and keyed to the axle 2.

Gear 25 is secured to the shaft 26 by a nut 32 threaded upon a reduced portion of said shaft and a washer 33 lying beneath said nut. At the other end of said shaft are a similar nut 34 and a washer 35, said washer being larger than the opening which receives the bearing 28 to thereby normally

prevent the shaft from moving endwise out of position in the casing. Bearing member 27 externally is as large or of slightly larger diameter than the pinion 29, so that said pinion can be removed endwise through the opening in which the bearing member 27 is seated. Bearing member 27 may also be secured to the casing body 4 by bolts 27^a passing through ears 27^b on said bearing member, as shown in Fig. 2.

The pinion 22 and gear 25 are preferably inclosed and protected in a suitable light hollow casing 36 made for example of thin sheet metal and supported by brackets 37 connected to the hollow casing.

The driving mechanism includes but a single intermediate shaft 26 and two pinions and two gears between the motor and axle. It is consequently simple and obtains the necessary speed reduction without undue loss of energy by friction in the gearing. Moreover, the pinion 29 and gear 30 are inclosed in a hollow casing which can serve as a reservoir for oil, grease, or other lubricant. Also, by removing the casing 36, nuts 23 and 32, and their washers, the pinion 22 and gear 25 can be readily taken off for repair or replacement. At the same time the bearing member 27 can be withdrawn from its opening, and by removing nut 34 and its washer the shaft 26 and the pinion 29 carried thereby can be taken out for like purposes. All parts are therefore readily accessible.

What I claim is:

1. In combination, a car having a frame and axle, a hollow casing supported by said frame and axle, a motor in said casing, and driving gears in said casing between said motor and axle, said casing being divided along a vertical plane through the axle for convenient access to the axle gear without disturbing the motor.
2. In combination, a car having a frame and axle, a hollow casing supported by said frame and axle, a motor in said casing, driving gears in said casing between said motor and axle, and a shaft in said casing supporting one of said gears and removable endwise from said casing.
3. In combination, a car having a frame and axle, a hollow casing supported by said

frame and axle, a motor in said casing, driving gears in said casing between said motor and axle, a shaft in said casing supporting one of said gears, and a bearing in said casing for said shaft, said bearing being as large as the shaft supported gear to permit removal of said gear and shaft from the casing.

4. In combination, a car having a frame and axle, a hollow casing supported thereby and carrying a motor, a shaft in said casing and projecting endwise therefrom, and co-operating gears on the motor shaft and casing shaft exposed outside of said casing and removable endwise from their respective shafts, said shaft being also removable endwise from the casing.

5. In combination, a car having a frame and axle, a hollow casing supported thereby and carrying a motor, a shaft in said casing and projecting endwise therefrom, co-operating gears on the motor shaft and casing shaft exposed outside of said casing and removable endwise from their respective shafts, and gears in said casing connecting said casing shaft and axle, said casing shaft and the gear carried thereby being removable endwise from said casing.

6. In combination, a car having a frame and axle, a casing having a body portion and axle housing portion secured to each other and completely surrounding said axle and provided with bearings therefor, a separate cap portion for said casing, a motor held between said cap and body portions, said cap portion being hinged to the body portion between the motor and axle, and gearing supported by said casing and connecting said motor and axle.

7. In combination, a car having a frame and axle, a casing supported at one end for swinging movement around said axle, a motor carried by said casing, gearing connecting said motor and axle, said axle having a reduced portion extending through the casing and beyond it at both sides forming shoulders, and split collars on the reduced portion of said shaft lying between said shoulders and the casing.

In testimony whereof I affix my signature.

SAMSON D. WRIGHT.
